Primary Examiner — Michael C Stout*Assistant Examiner* — Nicole M. Leech(74) *Attorney, Agent, or Firm* — MacCord Mason PLLC(57) **CLAIM**

The ornamental design for an angel decoration, as shown and described.

DESCRIPTION

FIG. 1 is a front perspective view of an angel decoration showing my new design;

FIG. 2 is a top view thereof;

FIG. 3 is a front view thereof;

FIG. 4 is a side view thereof;

FIG. 5 is an opposite side view thereof; and,

FIG. 6 is a front perspective view thereof, shown in a state of use.

The broken lines in the drawings represent portions of the angel decoration and form no part of the claimed design. The broken lines shown in FIG. 6 showing adornments represents environmental subject matter only and form no part of the claimed design.

1 Claim, 6 Drawing Sheets(56)
